P. S. BAUER.
AIR TIGHT RECEPTACLE.
APPLICATION FILED SEPT. 21, 1911.

1,107,746.

Patented Aug. 18, 1914.

UNITED STATES PATENT OFFICE.

PERRY S. BAUER, OF CHICAGO, ILLINOIS, ASSIGNOR TO BAUER & BLACK, OF CHICAGO, ILLINOIS, A CORPORATION OF ILLINOIS.

AIR-TIGHT RECEPTACLE.

1,107,746.

Specification of Letters Patent. Patented Aug. 18, 1914.

Application filed September 21, 1911. Serial No. 650,611.

To all whom it may concern:

Be it known that I, PERRY S. BAUER, a citizen of the United States, residing at Chicago, in the county of Cook and State of Illinois, have invented certain new and useful Improvements in Air-Tight Receptacles, of which the following is a specification.

This invention relates to receptacles adapted to be used for marketing various articles or substances which are required to be kept hermetically sealed until such time as they are to be used.

One of the objects of the invention is the provision of a receptacle of this character which shall be simple in construction, inexpensive to manufacture and which can be readily and quickly sealed after the contents have been placed therein and can be unsealed and opened without the employment of any tool or implement when the contents are to be used.

One form of my invention is shown in the drawings forming a part of this specification and from these drawings, when considered in connection with the following description, the invention will be understood and many of its advantages will be appreciated.

Referring to the drawings—Figure 1 is a perspective view of a receptacle embodying my invention and shown as closed and sealed. Fig. 2 is a similar view showing the receptacle in open position. Fig. 3 is a detail perspective view of the sealing strips. Fig. 4 is a transverse sectional view of the closed receptacle shown in Fig. 1; and Fig. 5 is a similar view of the receptacle after it has been unsealed.

From the drawings it will be observed that the receptacle comprises in general a body having end walls 5, a front wall 6 and a rear wall 7 of which the cover 8 forms an extension. The cover is provided at its free edge with a flap 9 and the end walls of the body 5 are provided with flaps 10 adapted to be inturned beneath the cover of the box into the position shown in dotted lines in Fig. 1. The body of the receptacle and the cover therefor are preferably formed from a single sheet of suitable material such as heavy paper or cardboard, for instance, the receptacle being formed by cutting a blank of suitable shape from the sheet of material and folding the blank to produce the box as shown in Fig. 2. The box is held together

by tabs or flaps which project inwardly from the front and rear walls 6 and 7 and are pasted or otherwise secured to the inner face of the end walls 5. The flaps indicated by reference character 11 in Fig. 2 are so shaped that their free edges abut on a median line of the end walls 5, but it will be obvious that the tabs or flaps 7 may be of any other desired or preferred configuration.

For the purpose of hermetically sealing the box and thereby producing an air-tight receptacle I employ one or more strips of paper, fabric or other suitable material which are folded longitudinally and secured throughout their length to the cover and body of the receptacle. One continuous strip of material can be folded so as to extend around the perimeter of the free edges of the box, if desired, but in the present instance, I have shown in Fig. 3 a plurality of strips of which the end strips 12 are the same length as the ends 5 of the box and the front strip 13 is the same length as the front wall 6 of the box. These strips are folded lengthwise one or more times, if desired, and are positioned upon a cord or string 14 as shown. After the receptacle is filled and the cover is closed the top and outer faces of the strips are coated with any suitable adhesive and the strips are then inserted between the cover and the body of the receptacle. The end strips 12 lie between the lower face of the cover and the upper face of the flaps 10 and the strip 13 lies between the outer face of the flap 9 and the inner face of the front wall 6 as shown in Fig. 1. The adhesive secures one face of each strip to the cover and the other face to the body of the box throughout its length, thereby effectually sealing the box and resulting in an air-tight receptacle. The position of the various parts when the box is sealed is shown in Figs. 1 and 4.

When it is desired to open the box the protruding end of the cord 14 may be grasped and pulled preferably in a direction at right angles to the face of the wall from which the cord protrudes. This action will tear the strips along the line of their folds thereby unsealing the receptacle so that it may be opened by lifting the cover. I have shown on the drawings both ends of the cord 14 as protruding, but it will be obvious that one protruding end is sufficient

and that by gripping this free end and pulling the same the strips will be severed and the receptacle unsealed.

Various changes in the size, shape, proportion and configuration of the various parts shown and described will suggest themselves to those familiar with the art, and it will be understood that my invention is not restricted to the exact disclosure of the drawings but is capable of considerable modification within the scope of the appended claims.

I claim:

1. An air tight receptacle comprising a body, a cover therefor, said body and cover having a pair of adjacent walls parallel each with the other, and a strip of flexible material folded upon itself between said cover and body to form a seal for the receptacle.

2. An air-tight receptacle, comprising a body, a cover therefor, a strip of material folded upon itself and interposed between the free edges of the cover and the corresponding free edges of the body and glued both to the body and the cover, and a cord positioned in the fold of said strip with one end protruding outside the receptacle where-

by said strip may be torn along its fold to unseal the receptacle.

3. An air-tight receptacle, comprising a body, a cover, a plurality of strips of folded material, each strip being connected with the cover and the body adjacent the free edges, and a cord arranged in the folds of said strips around the perimeter of the receptacle with one end protruding outside the receptacle to be gripped and pulled thereby tearing said strips along their folds to unseal the receptacle.

4. An air-tight receptacle comprising a body, a cover therefor having a flap adapted to be disposed within the body of the receptacle when the cover is closed, a strip of material folded upon itself and interposed between the said flap and the body of the receptacle and glued to said body and flap to seal the receptacle, and a cord positioned in a fold of the said strip with one end protruding outside the receptacle whereby the said strip may be torn along its fold to unseal the receptacle.

PERRY S. BAUER.
